ALBERT HENRY MIDGLEY, OF ACTON VALE, ENGLAND, ASSIGNOR OF ONE-HALF TO
CHARLES ANTHONY VANDERVELL, OF ACTON VALE, ENGLAND.

TIME-FUSE FOR SHELLS.

1,301,480.

Specification of Letters Patent. Patented Apr. 22, 1919.

Application filed May 23, 1917. Serial No. 170,543.

To all whom it may concern:

Be it known that I, ALBERT HENRY MIDGLEY, a subject of the King of Great Britain and Ireland, and residing at Warble Way, 5 Acton Vale, in the county of Middlesex, England, have invented certain new and useful Improvements in and Relating to Time-Fuses for Shells, of which the following is a specification.

10 This invention relates to time fuses for shells, and more particularly to lead or like covered fuses in which the timing is effected by punching the fuse at a point more or less distant from its point of connection with the 15 space communicating with the primer according to the time it is desired to lapse between the moment of firing and that of explosion.

In my concurrent application for Letters 20 Patent No. 170,542 I have described a time fuse comprising a lead or like covered fuse having two adjacent and relatively stationary portions separated from each other, with the exception of a small passage which can 25 be shifted between the two adjacent portions and through which the fuse is laterally punched at the required points.

Time fuses in which lead or like covered fuses are employed are sometimes rendered 30 inoperative by the flame being extinguished by the molten lead which is thrown about when the shell hits the ground and the main object of the present invention is to provide means by which this drawback is avoided.

35 According to the present invention, the lead or like covered fuse described in my prior specification No. 170,542 is modified by being composed of two parts, the two ends of the one part being connected with

40 the primer and the explosive in the shell respectively, while the other part of the fuse has one of its ends connected with the explosive in the shell, its other end being either free, or connected with the first part of the 45 fuse. One of the two parts of the fuse together with a portion of the other part is used as an adjustable time fuse and the whole of the latter part acts as a fuse of fixed timing.

50 Referring to the accompanying drawings which illustrate the invention by way of example:—

Figure 1 is a sectional elevation.

Fig. 2 is a sectional plan along the line

55 A B in Fig. 1.

Fig. 3 is a side elevation, and

Fig. 4 is a side elevation, partly in section, of the improved time fuse, Figs. 3 and 4 being views from opposite sides, while

Fig. 5 is a diagrammatic illustration of 60 the arrangement of the fuse within the fuse holder.

Referring to the drawings, *a* is the fuse holder which receives on its cylindrical periphery *b* a lead or like covered fuse comprising two parts, one part extending from the end *c*¹ communicating with the primer around the upper part of the fuse holder (see *c*² in Fig. 4) and then being bent down at *c*³ and continued along a short portion *c*⁴ 70 of the lower part of the fuse holder to the end *c*⁵ communicating with the explosive in the shell, the other part of the fuse extending from its free end *c*⁶ along the lower part of the fuse holder and terminating at its end 75 *c*⁷ which communicates with the explosive in the shell. The two parts of the fuse extending on the periphery of the fuse holder are adjacent and are separated from each other by an incomplete bi-partite flat ring *e* fitting 80 in a groove provided on the periphery of the fuse holder and adapted to be rotated between the adjacent portions of the fuse by means of a sleeve *f* provided with indentations *f*¹ engaging with projections *e*¹ provided on the separating ring *e*. At the point opposite the incomplete portion *e*² of the separating ring *e*, the sleeve *f* is provided with a guiding member *f*² provided with a guiding hole *f*³ of the required dimension to permit of a punch being inserted 85 therein for the purpose of laterally punching the two adjacent portions of the fuse.

The rotary sleeve *f* is prevented from axial movement by means of a retaining 95 ring *d*, sprung into a recess provided in the fuse holder above the sleeve *f*. The latter sleeve and the fixed fuse holder *a* are provided with an index *f*⁴ and with graduations *a*¹ respectively for the purpose of indicating the timing of the fuse which is determined by the position of the sleeve relatively to the holder.

The ends *c*⁵ and *c*⁶ of the two parts of the fuse preferably terminate into a ring *g* for 105 the purpose of directing the flame downward through the hole *g*¹ of the ring.

The striking mechanism of the fuse comprises a plunger *h* retained in its position by means of a safety-pin *i* provided with a 110

ring *i*, a plunger pin *j*, a percussion cap or primer *k* and a spring *l* interposed between the plunger and the percussion cap.

The operation of the time fuse hereinbefore described is similar to that of the time fuse described in my concurrent application above referred to, with the exception that when the fuse is punched, say, at a point *m* (see Fig. 5), the flame is divided at this point into two flames, the one flame continuing to traverse the main path along *c⁰*, *c¹*, while the other flame traverses the auxiliary path *c²*, *c³*, *c⁴*, *c⁵*, so that if the main path becomes inoperative owing to the flame of the burning fuse being extinguished by the molten lead when the shell hits the ground after the flame has passed the point *m*, the flame along the auxiliary path still continues to burn.

I wish it to be understood that the invention hereinbefore described is not limited to the mode of carrying it into effect above referred to and that the details of construction may be varied without in any way departing from the spirit of the invention. For instance, the lead or like covered fuse may be formed of one single piece bent back on itself in the shape of a hairpin as in my concurrent application No. 170,542, its two ends communicating with the primer and the explosive in the shell respectively and the bending point being connected by a separate continuation of the fuse with the explosive in the shell. In this case the punching is effected between the two adjacent portions of the hair-pin formation of the fuse which acts as an adjustable time fuse while one branch of these adjacent portions together with the continuation of the fuse above referred to serves as a fuse of fixed timing.

What I claim is:

1. A time fuse for explosive shells having a fuse holder, a covered fuse mounted on the fuse holder and having two adjacent parts, a gap in one of the two adjacent parts of the fuse, a movable member for covering the adjacent parts of the fuse and a punching hole in said movable member for punching the fuse laterally, as and for the purpose set forth.

2. A time fuse for shells having a fuse holder, a space provided in the fuse holder for receiving the primer, a space provided in the fuse holder for communicating with the explosive in the shell, a covered fuse mounted on the fuse holder and having two adjacent parts, a movable member for covering the adjacent parts of the fuse, a punching hole in the said movable member for punching the fuse laterally, one of the two adjacent parts of the fuse being interrupted by a gap, and the other part thereof, together with its continuation in the second part forming a fuse of fixed timing, its two

ends being connected with the space provided for the primer and with the space communicating with the explosive in the shell respectively, while a portion of the first part of the fuse, together with the disconnected portion of the second part thereof forms a fuse of adjustable timing, one end of which communicates with the space provided for the primer and is the same as the corresponding end of the fuse of fixed timing, while its other end is connected with the space communicating with the explosive, as and for the purpose set forth. 70

3. A time fuse for shells having a fuse holder, a covered fuse mounted thereon and having two adjacent parts, a gap in one of the two adjacent parts of the fuse, a separating movable member arranged between the adjacent parts of the fuse, an opening provided in said separating movable member, a movable member for covering the adjacent parts of the fuse, and a punching hole provided in the latter movable member and arranged to register with the opening in the separating movable member, as set forth. 75

4. A time fuse for shells having a fuse holder, a covered fuse mounted thereon, said fuse being bent back on itself in the form of a hairpin so as to have two adjacent parts, a gap in one of the adjacent parts of the fuse, a separating movable member arranged between the adjacent parts of the fuse, an opening provided in said separating movable member, a movable member for covering the adjacent parts of the fuse and a punching hole provided in the latter movable member and arranged to register with the opening in the separating movable member, as set forth. 95

5. A time fuse for shells having a fuse holder, a covered fuse mounted thereon and having two adjacent parts, a gap in one of the two adjacent parts of the fuse, a movable ring arranged between said adjacent parts of the fuse and formed with a gap, a movable member for covering the adjacent parts of the fuse, and a punching hole in the latter movable member arranged to register with the gap in the ring, as and for the purpose set forth. 105

6. A time fuse for shells having a fuse holder, an annular recess formed on the said fuse holder, a covered fuse mounted in said recess and having two adjacent parts, a gap in one of the two adjacent parts of the fuse, 110 a movable member for covering said recess and the adjacent parts of the fuse mounted therein, and a punching hole in said movable member for punching the adjacent parts of the fuse laterally, as set forth. 115

7. A time fuse for shells having a fuse holder, a recess formed on the cylindrical periphery of the fuse holder, a covered fuse mounted in said recess and having two adjacent parts, a gap in one of the two adjacent 120

parts of the fuse, a separating movable member arranged in said recess between the adjacent parts of the fuse, an opening in said separating movable member, a movable sleeve for covering the said recess and adjacent parts of the fuse mounted therein, and a punching hole in said sleeve arranged to register with the opening in the separating movable member, as and for the purpose set forth.

8. A time fuse for shells having a fuse holder, a recess formed on the periphery of the fuse holder, a covered fuse mounted in said recess and bent back on itself in the form of a hairpin so as to have adjacent parts, a gap in one of the two adjacent parts of the fuse, the radial depth of the recess receiving the fuse being made greater in the proximity of the bend of the fuse, a movable member for covering the recess and the adjacent parts of the fuse, and a punch-

ing hole in said movable member for punching the adjacent parts of the fuse laterally, as set forth.

9. A time fuse for shells having a fuse holder, an annular recess provided on the periphery of the fuse holder, a covered fuse mounted in the said recess and having two adjacent parts, a gap in one of the two adjacent parts of the fuse, a separating ring provided between the adjacent parts of the fuse and having a gap, a rotary sleeve for covering the said recess and the adjacent parts of the fuse, a punching hole in the said rotary sleeve arranged to register with the gap in the separating ring and means for connecting together the rotary sleeve and the ring, as and for the purpose set forth.

In testimony whereof I have signed my name to this specification.

ALBERT HENRY MIDGLEY.
